UNITED STATES PATENT OFFICE

2,416,771

CONCRETE MIXING AND DISTRIBUTING
APPARATUSDon C. Porter, Tacoma, Wash., assignor to Chain
Belt Company, Milwaukee, Wis., a corporation
of Wisconsin

Application April 21, 1944, Serial No. 532,125

1 Claim. (Cl. 259—160)

1

The invention relates to concrete mixing and distributing apparatus, and has for one of its objects to provide apparatus of this character which is mounted upon the chassis of a road vehicle for rapid transport from place to place, and in which, so far as mixing is concerned, the advantages accruing from feeding the raw materials in at one end of the machine and discharging the mixed concrete at the other end are secured, while as regards distribution of the mixture, the advantages of the well known tower and chute method are obtained.

A further object of the invention is to provide a highly mobile machine, the mixing and distributing unit of which is mounted upon the vehicle chassis for rotation about a substantially vertical axis whereby it may operate in nearly any horizontal angular relation to the chassis, thus materially reducing the movements of the vehicle incident to "spotting" the apparatus at the job.

Further objects of the invention are to provide an improved chassis construction for mounting an apparatus of the character described; to provide an improved tower construction; and to provide a machine capable of equalizing, at least to some extent, inequalities between the production and distribution of the mixture.

One form of apparatus constructed in accordance with the invention is illustrated in the accompanying drawings forming a part of this specification, in which like reference characters designate like parts in all the views, and in which:

Figure 1 is a side elevational view of the machine, with the parts shown in the positions they occupy during transport from place to place;

Fig. 2 is a similar view, showing the parts in their operative positions, the mixing and distributing unit having been swung through an angle of 180° relative to the supporting vehicle;

Fig. 3 is a horizontal sectional-plan view, partly diagrammatic, of the mixing and distributing unit.

Fig. 4 is an end elevational view of the apparatus, as seen from the left of Fig. 2;

Fig. 5 is a fragmentary vertical sectional view, taken approximately on the planes indicated by the line 5—5 of Fig. 3, looking in the direction of the arrows;

Fig. 6 is a plan view, partly in section, of the

forward portion of the vehicle chassis and its associated tongue structure;

Fig. 7 is an enlarged sectional view, taken on the plane indicated by the line 7—7 of Fig. 6; and

Fig. 8 is an end view of the parts shown in Fig. 7, as seen from the left thereof.

In the said drawings, 15 indicates the chassis of a road vehicle of the semi-trailer type, comprising longitudinal members 16 and cross members 17. The said chassis is mounted upon ground engaging wheels 18 and carries a pedestal structure 19 and a plurality of rollers 20 constituting a turntable upon which a framework 21 is mounted for horizontal rotational movement about a king pin 22. Within the said framework a conventional concrete mixing drum 23 is mounted upon rollers 24 for rotation about a horizontal axis, which drum has a charging chute or hopper 25 associated with a charging opening in one end wall of the drum. A charging skip 26, similar to those commonly employed with concrete mixers of the paving type, is pivotally mounted in the framework 21 at 27 and is adapted to be raised by means of cables 28 from a charge receiving position, such as is illustrated in Fig. 2, to an elevated position in which it discharges the materials into the chute 25 which conducts them to the interior of the drum.

An internal combustion engine or other suitable motor 30 is mounted on the framework 21, and as best shown in Fig. 3, drives a jack shaft 31 through a chain and sprocket drive 32. The said jack shaft drives a main shaft 33 through a chain and sprocket drive 34, which main shaft drives the mixing drum 23 through a chain and sprocket drive 35. The main shaft 33 carries the driving element of a friction clutch 36 which is adapted to be controlled by a fluid pressure cylinder and piston device 37; and the driven element of said clutch, through a chain and sprocket drive 38, drives a countershaft 39 which is provided with a friction brake 40 controlled by a fluid pressure cylinder and piston device 41. The countershaft 39 carries a bevel pinion 42 which meshes with a bevel gear 43 carried by a transverse shaft 44 which also carries a pair of winding drums 45 upon which the skip cables 28 are wound.

The opposite end wall of the drum 23 is provided with a discharge opening 50 (Fig. 4) adja-

cent which a discharge chute 51 (Fig. 5) is mounted by a shaft 52 for swinging movements into and out of the drum. The said chute may be operated by a fluid pressure piston and cylinder device 57 or by means of any appropriate power driven mechanism, such for example as that disclosed in U. S. Patent No. 1,415,411, granted May 9, 1922. A bin or receptacle 53 is mounted in the framework 21 in position to receive the concrete discharged from the drum by the chute 51, which receptacle has a discharge passage 54 normally closed by a gate 55 controlled by a fluid pressure cylinder and piston device 56.

At the rear end of the framework 21 twin laterally spaced skeleton towers 60 are pivotally connected at 61 to base structures 62 incorporated into said framework, which towers are connected at their upper ends by a cat head 63. The towers are preferably constructed in sections which may be joined by suitable connections 64, and the cat head 63 is arranged to slide upon the towers, whereby sections may be added to or removed from them to increase or decrease their overall height. Fluid pressure cylinder and piston devices 65, pivotally connected at 66 to the framework 21 and at 67 to the towers, are provided for raising and lowering the towers about their pivotal connections 61, between a horizontal traveling position (shown in Fig. 1) and a vertical operating position, shown in Figs. 2, 3 and 4.

Each tower structure 60 is provided with vertical guide members 70 and 71 which, in the elevated position of the towers, align with and form continuations of like guide members 70' and 71' respectively, carried by the base structures 62. A hoist bucket 72 is slidably mounted upon the forward pair of guides 71, being movable up and down thereon by a hoist cable 73 which is trained over sheaves 74 carried by the cat head 63 and extends downwardly through one of the tower structures 60 to a winding drum 75 disposed in the base 62 of such tower. Said drum is mounted upon a shaft 76 journaled on the frame 21, and a clutch 77 is provided for coupling the shaft and drum, which clutch is adapted to be engaged and disengaged by means of a fluid pressure cylinder and piston device 78. The drum is also provided with a friction brake 79 whereby it may be locked against rotation, which brake is controlled by a fluid pressure cylinder and piston device 80.

The rearward guide members 70, 70' constitute a trackway for a distributing hopper 85, having a discharge controlling gate 86. In the operative position of the parts, this hopper is elevated to any desired height (up to a point just below the cat head 63, as shown in Fig. 4) by a cable 87 anchored to the cat head and trained about sheaves 88 carried by the hopper, and a sheave 89 mounted on the cat head, from which it extends downwardly within the other tower 60 to a winding drum 90 located within the base structure 62 of such tower (see Fig. 3). This drum is carried by a shaft 91 to which it may be coupled by a clutch 92, and a friction brake 93 is provided to lock the drum against rotation when desired. The shafts 76 and 91 are driven from the mixing drum 23 by a chain and sprocket drive 94.

In the traveling position of the parts the distributing hopper 85 is lowered to a position adjacent the base structures 62 of the towers, as shown in Fig. 1, being here guided and supported by the fixed guide members 70' carried by such structures. The hoisting bucket 72 is likewise positioned adjacent the tower bases on the fixed guide members 71', and the towers 60 may then be

lowered by their fluid pressure devices 65 to the horizontal position shown in Fig. 1. The charging skip 26 is partially raised and held by the brake 40 in substantially the position shown in said figure.

The frame 21 and the parts carried thereby are rotatable on the turntable structure 19, 20, 22 through 360°, and since the bucket 72 must be lowered to ground level, as shown in Figs. 2 and 4, to receive a batch from the receptacle 53, in order that the apparatus may be operative when turned to the position shown in these figures, the chassis 15 of the semi-trailer is constructed to provide an open space or well 100 at its forward end through which the said bucket may be lowered.

The chassis 15 is provided with a tongue structure 101 having a suitable coupling 102 for readily detachable connection to any appropriate form of tractor road vehicle (not shown) which tongue normally projects forwardly as illustrated in Fig. 1. However, in order that the skip 26 may be lowered to charge-receiving position when the frame 21 is in the Fig. 1 position relative to the trailer, the tongue structure 101 is retractably mounted on the longitudinal members 16 of the chassis by rollers 105. The tongue may thus be moved rearwardly, i. e., toward the right as viewed in Fig. 1, to a position in which it will clear the skip when the latter is lowered to the Fig. 2 position.

Jacks or equivalent adjustable supports 106 are preferably provided at each corner of the frame 21, for engagement with the ground surface during operation of the machine, as shown in Fig. 2, to stabilize the apparatus and take the load off the tires of the trailer wheels 18.

The receptacle 53 provides a storage chamber tending to smooth out inequalities between production and distribution of the mixture. That is to say, at times the supply of raw materials to the skip 26 may lag, during which, for at least short periods, distribution by means of the bucket 72 and hopper 85 may continue by drawing on the reserve in chamber 53. At other times distribution may be temporarily held up, whereupon concrete from the drum 23 may be accumulated in the said chamber.

Any well known form of chuting arrangement, such as is widely used in stationary tower distribution systems, may be attached to the towers 60 in position to receive the concrete from the hopper 85 and conduct it by gravity to the point of use.

The fluid pressure devices 65 are preferably hydraulic, and for supplying liquid under pressure for their operation, a pump 110 (Fig. 3) may be provided, driven by a chain and sprocket drive 111 from the shaft 31. The fluid pressure devices 37, 41, 56, 57, 78 and 80 may be hydraulic, in which case they would also be supplied by the pump 110; but they are preferably pneumatic, being supplied with air under pressure by an air compressor 112, also driven from the shaft 31 by a chain and sprocket drive 113. The fluid connections to the several devices may be conventional and are not shown.

What is claimed is:

In a mobile concrete mixing and distributing apparatus having a framework, and a power-driven mixing drum mounted thereon: a pair of laterally spaced skeleton towers respectively hinged to base structures carried by said framework and movable between a horizontal inoperative position and a vertical operative position; power means for raising and lowering said tower

structures in unison; an elevating bucket and a distributing hopper each slidably mounted by the towers between them; a hoisting mechanism disposed in each of the tower base structures, for raising and lowering the bucket and hopper respectively; and common means for driving said hoisting mechanisms from the mixing drum.
